US00D739347S

(12) **United States Design Patent**
Huang et al.

(10) **Patent No.:** US D739,347 S
(45) **Date of Patent:** ** Sep. 22, 2015

(54) **POWER SUPPLY**

(71) Applicant: **DELTA ELECTRONICS, INC.**,
Taoyuan Hsien (TW)

(72) Inventors: **Yen-Wen Huang**, Taoyuan Hsien (TW);
Hon-Ji Chen, Taoyuan Hsien (TW);
Hsueh-Tsung Lu, Taoyuan Hsien (TW);
Po-Ching Wang, Taoyuan Hsien (TW)

(73) Assignee: **DELTA ELECTRONICS, INC.**,
Taoyuan Hsien (TW)

(**) Term: **14 Years**

(21) Appl. No.: **29/513,096**

(22) Filed: **Dec. 26, 2014**

(51) LOC (10) Cl. **13-02**

(52) U.S. Cl.

USPC **D13/110**

(57) **CLAIM**

The ornamental design for a power supply, as shown and described.

DESCRIPTION

FIG. 1 is a perspective view of a power supply showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

The broken lines shown represent unclaimed subject matter and form no part of the claimed design.
